UNITED STATES PATENT OFFICE.

EDWARD M. BURD, OF JACKSON, MICHIGAN, ASSIGNOR TO ALLIS-CHALMERS MANUFACTURING COMPANY, OF MILWAUKEE, WISCONSIN, A CORPORATION OF DELAWARE.

HYDRAULIC MACHINE.

Application filed August 12, 1927. Serial No. 212,383.

This invention relates in general to improved means for preventing excessive leakage of liquid in hydraulic machines, and relates more specifically to improvements in 5 the construction and operation of packing or sealing devices for closing the clearance gaps between the ends of a series of flow controlling vanes and the adjacent casings.

The universal practice in the art of hydraulics, and especially in the construction of reaction hydraulic turbines, is to utilize an annular series of movable guide vanes cooperating with stationary side plates located at the ends of the vanes, to control the admission of liquid to the turbine rotor. The successive guide vanes of the series are ordinarily pivotally adjustable about parallel axes, and a slight clearance is usually provided between the ends of each vane and the adjacent side plates. When the vanes are in closed position, the adjacent vanes coact with each other to shut off the major portion of the flow, but the working clearances at the ends of the vanes allow considerable liquid 20 to leak from the supply or other liquid containing conduit into the rotor chamber.

It is an object of the present invention to provide simple and efficient means for eliminating excessive leakage of liquid past 30 the ends of the flow controlling guide vanes of a hydraulic machine, when the vanes are in closed position. A further object of the invention is to provide sealing means which may be conveniently applied either to a new 35 machine in the course of manufacture thereof, or to a machine which has been installed and placed in operation. Another object of the invention is to provide a series of leakage eliminating strips cooperable with the 40 guide vanes and casing of a turbine or the like, which may be readily adjusted and replaced when worn. These and other objects and advantages of the invention will be apparent from the following description.

A clear conception of several embodiments of the invention may be had by referring to the drawing accompanying and forming a part of this specification, in which like reference characters designate the same or similar 45 parts in the various views.

Fig. 1 is a central vertical section through a reaction hydraulic turbine installation having the improved sealing strips applied therein.

Fig. 2 is an enlarged fragmentary top view

of a series of flow controlling guide vanes and a side plate cooperating therewith, showing the application of one form of the improved sealing strips.

Fig. 3 is an enlarged fragmentary sectional view showing the mode of coaction of one form of the improved sealing strip with a guide vane when in closed position.

Fig. 4 is an enlarged fragmentary top view of another form of the improved sealing strips, showing the same cooperating with guide vanes.

Fig. 5 is an enlarged fragmentary sectional view showing the cooperation between the form of sealing strip disclosed in Fig. 4, with a guide vane and side plate.

The hydraulic turbine installation specifically illustrated in Fig. 1 comprises in general a rotor 2 secured to a main shaft 6 and adapted to receive actuating liquid from a supply conduit 3 and to deliver the liquid to a draft tube 4. Located between the supply conduit 3 and the inlet edges of the vanes of the rotor 2, is an annular series of movable guide vanes 5, each of which is pivotally supported by means of a stem 11. The stems 11 are journaled in top and bottom plates 7, 8 respectively, and are provided at their upper ends with actuating arms 12. The actuating arms 12 are operatively connected to a common actuating ring 13, which is rotatably supported upon the main turbine casing. The main turbine casing besides providing a support for the ring 13, also carries a bearing 14 for the main shaft 6.

As illustrated in Figs. 1, 2 and 3, the top and bottom plates 7, 8 of the turbine casing, are each provided with an annular series of sealing strips 9 cooperable with the outer end edges of the vanes 5 when these vanes are in closed position as shown in Fig. 2, and are also provided with an annular series of sealing strips 10 cooperable with the inner end edges of the guide vanes 5. The strips 9, 10 may be secured to the plates 7, 8 in any convenient manner, as by riveting, welding or otherwise, there being two oppositely disposed strips 9, 10 cooperable with each end of each vane 5.

As illustrated in Figs. 4 and 5, the top and bottom plates 7, 8 of the turbine casing, are each provided with an annular series of sealing strips 15 cooperable with the outer end edges of the vanes 5 when these vanes are in closed position as shown in Fig. 4, and are

also provided with an angular series of sealing strips 16 cooperable with the inner end edges of the guide vanes 5. The strips 15, 16 are preferably secured to the side plates 7, 8, by means of screws 17 coacting with elongated openings 18 in the strips 15, 16. By virtue of the screws 17 and the openings 18, the strips 15, 16 may be adjusted to snugly fit the adjacent vane edges.

10 During the normal operation of the turbine, the guide vanes 5 are in open position as indicated in dot and dash lines in Fig. 2, and liquid is being delivered from the supply conduit 3 to the rotor 2, through the spaces between the successive vanes 5. The guide vanes 5 are adjustable about their pivotal axes by means of the actuating ring 13 and the arms 12 cooperating with the pivot stems 11. When the guide vanes are closed, 20 they cooperate with each other to cut off the major portion of the flow, and the end edges of the guide vanes 5 engage the adjacent sealing strips to effectively reduce to a minimum, the leakage past the ends of the vanes. While 25 the sealing strips may not entirely close the passages at the ends of the vanes, due to the fact that it is difficult in commercial practice to cause these strips to extend directly in contact with the vane actuating stems 11, the 30 strips do in fact reduce the leakage to such an extent that it is unobjectionable.

From the foregoing description it will be apparent that the sealing strips may be either firmly attached to the side plates 7, 8 as disclosed in Figs. 1, 2 and 3, or they may be adjustably associated with the plates 7, 8 as disclosed in Figs. 3 and 4. The sealing strips may obviously be applied either to the plates while the turbine is being manufactured, or 40 they may be applied to existing installations. The strips in no manner affect the normal operation of the turbine and may readily be replaced when worn.

It should be understood that it is not desired to limit the invention to the exact details of construction and operation herein shown and described, for various modifications within the scope of the claims may occur to persons skilled in the art.

50 It is claimed and desired to secure by Letters Patent:

1. In combination, a rotor, a series of movable guide vanes for controlling the flow of liquid with respect to said rotor, stationary side plates located adjacent to the opposite ends of said vanes, and sealing means secured to said plates and cooperating with said vane ends to prevent flow of liquid past the vane ends when said vanes are in closed position.

60 2. In combination, a rotor, a series of pivotally supported guide vanes for controlling the flow of liquid to said rotor, stationary side plates located adjacent to the opposite ends of said vanes, and sealing strips secured to said plates and cooperating with said vane

ends to prevent flow of liquid past the vane ends when said vanes are in closed position.

3. In combination, a rotor, a series of pivotally supported guide vanes for controlling the flow of liquid to said rotor, side plates located adjacent to the ends of said vanes, sealing strips secured to said plates and cooperating with said vane ends to prevent flow of liquid past the vane ends when said vanes are in closed position, and means for effecting adjustment of said strips relative to said vanes and said casings.

4. In combination, a rotor, a series of movable guide vanes for controlling the flow of liquid with respect to said rotor, side plates located adjacent to the ends of said vanes, and a pair of sealing strips cooperating with the opposite sides of each vane to prevent flow of liquid past the vane ends when said vanes are in closed position.

5. In combination, a rotor, a series of pivotally supported guide vanes for controlling the flow of liquid to said rotor, side plates located adjacent to the ends of said vanes, and a pair of sealing strips secured to said plates and cooperating with the opposite sides of each of said vanes to prevent flow of liquid past the vane ends when said vanes are in closed position.

6. In combination, a rotor, a series of pivotally supported guide vanes for controlling the flow of liquid to said rotor, side plates located adjacent to the ends of said vanes, a pair of sealing strips secured to said plates and cooperating with the opposite sides of each of said vanes to prevent flow of liquid past the vane ends when said vanes are in closed position, and means for effecting adjustment of said strips relative to said vanes and said casings.

7. In combination, a rotor, a series of movable guide vanes for controlling the flow of liquid with respect to said rotor, side plates located adjacent to the ends of said vanes, and a pair of sealing strips secured to each of said plates and cooperating with the opposite sides of each vane to prevent flow of liquid past the vane ends when said vanes are in closed position.

8. In combination, a rotor, a series of movable guide vanes for controlling the flow of liquid with respect to said rotor, side plates located adjacent to the ends of said vanes, a pair of sealing strips secured to each of said plates and cooperating with the opposite sides of each vane to prevent the flow of liquid past the vane ends when said vanes are in closed position, and means for effecting adjustment of said strips relative to said vanes and said casings.

9. In combination, a rotor, a series of pivotally supported guide vanes for controlling the flow of liquid to said rotor, side plates located adjacent to the ends of said vanes, and a pair of sealing strips secured to each of said

plates on the opposite sides of each vane pivot and cooperating with the opposite sides of each vane to prevent flow of liquid past the vane ends when said vanes are in closed position.

10. In combination, a rotor, a series of pivotally supported guide vanes for controlling the flow of liquid to said rotor, side plates located adjacent to the ends of said vanes, a pair of sealing strips secured to each of said

plates on the opposite sides of each vane pivot and cooperating with the opposite sides of each vane to prevent flow of liquid past the vane ends when said vanes are in closed position, and means for effecting adjustment of 15 said strips relative to said vanes and said casings.

In testimony whereof, the signature of the inventor is affixed hereto.

EDWARD M. BURD.
